DESIGN FOR A REDINGOTE

Edna Breer, New York, N. Y.

Application January 17, 1941, Serial No. 98,137

Term of patent 3½ years

To all whom it may concern:

Be it known that I, Edna Breer, a citizen of the United States and a resident of the city of New York, in the county of New York and State of New York, have invented a new, original, and ornamental Design for a Redingote, of which the following is a specification, reference being had to the accompanying drawing, forming a part thereof.

Fig. 1 is a front view of a redingote showing my new design.

Fig. 2 is a rear view of the redingote as shown in Fig. 1.

I claim:

The ornamental design for a redingote, substantially as shown.

EDNA BREER.
